[57] CLAIM

The ornamental design for a coin acceptor or similar article, substantially as shown and described.

DESCRIPTION

FIG. 1 is a right perspective view of a coin acceptor or similar article, showing my new design;

FIG. 2 is a top plan view thereof, the bottom being flat, plain and unornamental;

FIG. 3 is a right side elevational view thereof;

FIG. 4 is a left side elevational view thereof;

FIG. 5 is a rear elevational view thereof; and

FIG. 6 is a front elevational view thereof.
